UNITED STATES PATENT OFFICE

2,593,710

DOOR OPERATOR

Frederick James Warner, Mansfield, England

Application December 18, 1947, Serial No. 792,495
In Great Britain October 16, 1944Section 1, Public Law 690, August 8, 1946
Patent expires October 16, 1964

6 Claims. (Cl. 268—36)

1

This invention is for improvements in and applicable to doors and has particular reference to ventilation doors in coal mines. It is well known that it is customary in coal mines to provide hinged doors which must normally be maintained closed for ventilation purposes; at intervals pit tubs have to pass through such doors, and according to customary practice the opening and closing of these doors is controlled by an operator. An object of this invention is to dispense with the service of an operator for each door and to provide means whereby the tubs or the like themselves control the opening and closing of the doors.

According to this invention there is provided apparatus for automatically operating hinged doors normally disposed in the path of rolling stock such as pit tubs, comprising a lever device pivoted intermediate its ends, one of said ends being normally disposed in the path of tubs approaching the door and also arranged to overlap the door when the door is fully open, and means connecting the other end of said lever device to the door at a position on said door remote from the hinge thereof.

It will be appreciated that by this arrangement tubs approaching the doors make contact with and actuate said lever automatically to open the door, and when the door is fully open the lever overlaps the door; this ensures that when the tubs reach the free end of the open door said door is out of line of the movement of the tubs. Preferably the lever is connected to the door by a rigid link or connecting rod.

The hinged door may have connected with it an additional hinged door in such manner that the two doors together constitute double doors and the invention therefore also provides apparatus for automatically operating double hinged doors normally disposed in the path of rolling stock such as pit tubs, comprising a lever device pivoted intermediate its ends one of said ends being normally disposed in the path of tubs approaching the doors and arranged to overlap one of the doors when said door is fully open, means for connecting the other end of said lever device to said door at a position on the door remote from the hinge thereof and means connecting the two doors for simultaneous operation.

Means may also be provided for causing the single door or the double doors to be opened by a tub travelling in either of two directions.

The invention therefore further provides apparatus for automatically operating hinged doors normally disposed in the path of rolling stock

2

such as pit tubs, comprising a lever device pivoted intermediate its ends one of said ends being normally disposed in the path of tubs approaching the doors in one direction and arranged to overlap the door when the door is fully open, means connecting the other end of said lever device to the door at a location on said door remote from the hinge thereof and means for transmitting motion to the door from a tub travelling in the opposite direction.

In order that the nature of the invention may be more readily understood, a particular embodiment will now be described by way of example with reference to the accompanying drawings

15 in which:

Figure 1 is an elevational view.

Figure 2 is a plan view.

Figures 3 and 4 are detail views on an enlarged scale.

20 Figure 5 is a plan view of a modification.

The door 1 which may be of wood or other suitable material is provided with a fixed front plate 2 and back plate 3 and is hung on hinges 4 and 4a; door jambs are provided at 5. The 25 door frame is not set vertical but slopes backwardly, a suitable angle of slope being indicated at Y in Figure 1 and from Figures 1 and 2 it will be seen that the lower hinge 4a is set outwardly further from the frame than the upper hinge 4. Extending from the front plate 2 is a lug 6, and said lug and the bifurcated head 7 of an adjustment screw 8 are transfixied by a pin 9. This adjustment screw is received in one 30 end of a link or connecting rod 10 the other end of which is pivotally connected at 14 to a lever 11 fulcrumed at 12; the function of the screw 8 is to vary the effective length of the link 10. Fulcrum pin 12 which is preferably formed with oil grooves (not shown) is fixed such as by

35 screw thread and split pin in a stirrup 12a riveted to a mild steel plate 12b secured by rag bolts (not shown) on the upper plain surface of a concrete foundation 13. The lever 11 is conveniently formed by riveting or welding two 40 lengths of angle iron together and is formed with a boss 11a for the reception of pin 12. The end 15 of such lever remote from the pivot 14 is curved and tapered as shown and is normally disposed midway in the track 16 along which 45

50 the tubs 17 travel and approximately midway in the height of the tub bodies. On the back of the door is mounted a bumper 18 (Figure 2) preferably of spring steel; the height of this bumper is determined by the height of the tubs which 55 are to pass through the door.

It will be seen from Figures 3 and 4 that the lug 6 is of tapered configuration; the pin 9 is a comparatively loose fit in the bifurcated head 7 so that the link 10 and lug 6 are capable of slight movement in a vertical plane relatively to one another. Grooves are formed in the door sill for the accommodation of the rails 16 and haulage rope 19 so that the door is a good fit when closed.

The manner of operation is as follows: As a tub approaches the door it engages the end 15 of lever 11 and rotates the latter about its fulcrum 12 with the result that through the intermediary of link 10 the door 1 is opened and is moved through approximately 90° by the time the end of the tub has moved past the end of the lever.

The arrangement and disposition of the parts is such that the curved end of the lever overlaps and bears upon the end of the door remote from its hinges when the door is opened, as is clearly shown in chain lines in Figure 2. As the tub continues in its travel the curved end 15 of the lever rides along the near side of the tub thus holding the door open and such side of the tub then rubs along the bumper 18 after riding off the end of the lever. The door is thus maintained fully opened until the tub (or the last tub if a line of tubs is being hauled) has passed through the door, when the door automatically swings back to the closed position. At the same time the lever is restored to its starting position and in this manner as successive tubs or lines of tubs approach the door the door is automatically opened to allow the passage thereof and immediately afterwards the door automatically closes.

It will be appreciated that as the door is being opened there would be a risk of it fouling the haulage rope 19 if the door did not rise and it is for this reason that the frame is set back and the hinges are disposed as described. Furthermore consequent upon this rise of the door in opening it is necessary to allow for relative movement between link 10 and lug 6 and it is for this reason that the lug is tapered and fitted in the manner described.

In the construction shown in Figure 5 an additional hinged door 20 is provided associated with the door 1 (hereinafter referred to as the main door) to provide double doors. These double doors are provided transversely across the track 16 in such manner that their hinges 4, 4a, 21, 21a, are located outside the track and their free ends 22, 23 meet at a location substantially centrally between the rails of the track. In the closed position the two doors 1, 20 are substantially in alignment. The main door 1 is constructed and arranged as above described insomuch as it is connected by the rigid link 10 (which is disposed in front of the door and is adjustable for length as previously described) to one end 14 of the double armed lever 11 (also disposed at the front of the door) and the other end 15 of which is located in the path of an approaching tub 17 or the like, the arrangement being such that the approaching tub 17 engages the lever 11 to open the said main door 1 and that the said lever 11 overlaps the door when the door is open.

The other hinged door 20, hereinafter referred to as the additional door, is connected to the main door 1 by a rigid connecting link 24 in such manner that when the main door opens or closes complementary opening and closing movements are automatically imparted to the additional

door 20. For this purpose the link 24 is disposed at the rear of the doors and its innermost end 25 is pivotally connected to a comparatively small bracket 26 fixed to the main door at the upper end thereof and located substantially centrally of its width.

From this bracket 26 the link 24 extends transversely across the track 16 and substantially parallel to the additional door 20 to a location 27 spaced rearwardly from the hinges 21, 21a and spaced slightly further away from the track than the hinges. At this location 27 the end of the link is pivotally connected to the outer end of a suitable bracket 28 which is secured to the additional door 20 at its upper end. It will be understood from consideration of this arrangement that when the tub 17 approaches the front of the doors it automatically opens the main door 1 as previously described and this opening movement of the main door is imparted by the link 24 connecting the two doors to the additional door 20 in such manner as to cause this additional door to open simultaneously with the main door. The connecting link 24 is preferably adjustable for length by being provided in two parts 24, 24a, which have a screw threaded engagement with each other; by this means the extent to which the additional door 20 opens may be adjusted to ensure that it is out of line of the passing tub when the door 20 is in its fully open position. It is also to be understood that the link 24 connecting the two doors is located at such a height that when the doors are open the tubs pass beneath it without touching it. A suitable stop 29 may be provided with which the additional door 20 may engage when fully open, and a bumper guard 30 is preferably provided on the rear face of the door 20 as a protection against the door being damaged by a passing tub.

The arrangement above described or the arrangement shown in Figures 1 to 4 is readily adaptable for a double road haulage system, that is to say wherein tubs or the like may travel along the track in either of two opposite directions, and by way of example a double track system is shown in Figure 5 as applied to double doors. It has already been described how the doors may be opened by a tub approaching the front of the doors and in order to cause the necessary opening movement of the doors automatically when a tub approaches the rear of the doors (i. e. in the opposite direction) an additional double armed lever 31 is provided located at the rear of the doors and its free end 32 is disposed in the path of a tub 33 approaching from the rear; its other end 34 is connected by an adjustable link to the first mentioned double arm lever 11 located at the front of the doors and the arrangement is therefore such that when a tub 33 approaches the rear of the doors it rocks the additional double armed lever 31 which through the medium of the said adjustable link 35 rocks the first mentioned lever 11 to open the doors in the manner previously described.

If desired there may be provided one or more springs to assist in closing the doors, e. g. there may be a leaf spring 36 fixed in such a position as to be flexed by the main door at the end of its opening movement and said spring being then so flexed as to impart an initial closing movement to the doors when a tub has passed.

If desired also any or all of the adjustable links, and particularly the link 10 connecting the

main door 1 to its operating lever 11 may have a shock absorbing device incorporated in it, e. g. a coil spring 31 may be provided at the junction of the two parts 8 and 10 forming the link.

Each or any of the levers 11, 31, may carry at its free end a roller or ball which partly projects so as to constitute a bearing surface for engagement by approaching tubs.

I claim:

1. A device for automatically opening a door pivotally mounted for movement over a path having a center line which passes beneath a central portion of the door frame in which the door is mounted, comprising, in combination, an elongated lever having one end portion pivotally mounted for movement over the path and located ahead of the door, said one end portion of said lever being movable between a first position when the door is closed and a second position when the door is fully opened; and link means having one end portion pivotally connected to said lever and another end portion pivotally connected to the door, said other end portion of said link means being movable between a first position when the door is closed and a second position when the door is fully opened, and said second position of said other end portion of said link means being located at a greater distance from the center line of the path than said second position of said one end portion of said lever.

2. A device for automatically opening a door pivotally mounted adjacent a vertical edge thereof for substantially horizontal swinging movement over a path leading through the door, comprising, in combination, a lever pivotally mounted intermediate its ends at a point located adjacent to the path and ahead of the door, said lever having a first portion extending from the pivotal mounting thereof to a point located over the path and having a second portion extending from the pivotal mounting thereof in a direction away from the path, said first portion of said lever being longer than the difference between the width of the door and the distance between said pivotal mounting of said lever and the pivotal mounting of the door; and a link pivotally connected at one end portion thereof to said second portion of said lever and at the other end portion thereof to said door, whereby when said first portion of said lever is actuated to move the door to its fully open position, said first portion of said lever overlaps said door.

3. A device for automatically opening a door pivotally mounted adjacent a vertical edge thereof for substantially horizontal swinging movement over a path leading through the door, comprising, in combination, a lever pivotally mounted intermediate its ends at a point located adjacent to the path and ahead of the door, said lever having a first portion extending from the pivotal mounting thereof to a point located over the path and having a second portion extending from the pivotal mounting thereof in a direction away from the path, said first portion of said lever being longer than the difference between the width of the door and the distance between said pivotal mounting of said lever and the pivotal mounting of the door; and a link pivotally connected at one end portion thereof to said second portion of said lever and at the other end portion thereof to said door, whereby when said first portion of said lever is actuated to move the door to its fully open position, said first portion of said lever overlaps said door and is located between the door and path so that the door cannot move toward

the path until the object actuating the lever is out of contact with said first portion thereof.

4. A device for automatically opening a door pivotally mounted adjacent a vertical edge thereof for substantially horizontal swinging movement over a path leading through the door, comprising, in combination, a lever pivotally mounted intermediate its ends at a point located adjacent to the path and ahead of the door, said lever having a first portion extending from the pivotal mounting thereof to a point located over the path and which is located above said path by a distance approximating one half of the height of the door and said lever having a second portion extending from the pivotal mounting thereof in a direction away from the path, said first portion of said lever being longer than the difference between the width of the door and the distance between said pivotal mounting of said lever and the pivotal mounting of the door; and a link pivotally connected at one end portion thereof to said second portion of said lever and at the other end portion thereof to said door, whereby when said first portion of said lever is actuated to move the door to its fully open position, said first portion of said lever overlaps said door and is located between the door and path so that the door cannot move toward the path until the object actuating the lever is out of contact with said first portion thereof.

5. A device for automatically opening a door pivotally mounted adjacent a vertical edge thereof for substantially horizontal swinging movement over a path leading through the door, comprising, in combination, a lever pivotally mounted intermediate its ends at a point located adjacent to the path and ahead of the door on one side thereof, said lever having a first portion extending from the pivotal mounting thereof to a point located over the path and which is located above said path by a distance approximating one half of the height of the door and said lever having a second portion extending from the pivotal mounting thereof in a direction away from the path, said first portion of said lever being longer than the difference between the width of the door and the distance between said pivotal mounting of said lever and the pivotal mounting of the door; a link pivotally connected at one end portion thereof to said second portion of said lever and at the other end portion thereof to said door, whereby when said first portion of said lever is actuated to move the door to its fully open position, said first portion of said lever overlaps said door and is located between the door and path so that the door cannot move toward the path until the object actuating the lever is out of contact with said first portion thereof; and means located on the other side of the door and operatively connected to said lever for actuating the same when an object approaches the door from the other side thereof.

6. A device for automatically opening a pair of doors each pivotally mounted adjacent a vertical edge thereof for substantially horizontal swinging movement over a path leading through the door, comprising, in combination, a lever pivotally mounted intermediate its ends at a point located adjacent to the path, said lever having a first portion extending from the pivotal mounting thereof to a point located over the path and having a second portion extending from the pivotal mounting thereof in a direction away from the path, said first portion of said lever being longer than the difference between the width of one of

the doors and the distance between said pivotal mounting of said lever and the pivotal mounting of the said one of said doors; a link pivotally connected at one end portion thereof to said second portion of said lever and at the other end portion thereof to said one of said doors; and linkage means interconnecting said doors for opening and closing the other of said doors in response to opening and closing movement of said one of said doors.
